UNITED STATES PATENT OFFICE.

JULIUS DEBRINKE, OF SALT LAKE CITY, UTAH TERRITORY.

WATCH-PROTECTOR.

SPECIFICATION forming part of Letters Patent No. 380,869, dated April 10, 1888.

Application filed June 23, 1887. Serial No. 242,247. (No model.)

To all whom it may concern:

Be it known that I, JULIUS DEBRINKE, a citizen of Turkey, who have declared my intention to become a citizen of the United States, residing in Salt Lake City, in the county of Salt Lake and Territory of Utah, have invented certain new and useful Improvements in Watch-Protectors, of which the following is a specification.

10 My invention relates to that class of inclosing-protectors for watches which are made from soft material and are designed in part to protect the polished case of the watch against injury or abrasion, in part to prevent the watch 15 from slipping too readily from the pocket, and in part to conceal the character of the watch from dishonest persons.

20 My object is to provide a protector that will not interfere in any material degree with the opening of the cap of the watch-case, and will yet protect the case at all times in the manner and for the purposes above stated.

25 My invention will be hereinafter fully described, and its novel features carefully defined in the claims.

30 In the drawings which serve to illustrate my invention Figure 1 is a plan or top view of a protector for a watch-case in which my invention is embodied. Fig. 2 is a front view 35 of said protector. These views show the protector only. Fig. 3 is a side or edge view of the protector inclosing a watch. Fig. 4 is a sectional view of the protector shown as inclosing a watch. In this view the watch is seen in edge elevation with the face-cap thrown up by its spring. Fig. 5 illustrates a form of my protector as adapted to an open-face key-winding watch. The watch is in elevation and the protector in section in this view.

40 I prefer to construct the shell of my protector from leather, but any similar material will serve, provided it is of a somewhat soft and yielding character and does not contain chemical substances that will corrode or tarnish the metal of the watch.

45 In carrying out my invention I prefer to press or stamp up two like or similar concave parts or halves from leather and join them at their margins by stitches or with cement.

50 A is a protector so formed, a' being one of

the two parts or sections thereof, and a² the other part or section. This protector will of course have the proper form and capacity to fit more or less snugly the watch it is to contain. I line the shell of the casing thus formed 55 with chamois-skin a³, and I prefer to apply this lining to the material that is to form the parts or sections of the shell before the stamping or pressing of the latter, but it might be done afterward.

60 B is an ordinary "hunting-case" watch, which has a stem-winding pendant, b, and a cap, b², that is thrown up by a spring when released by pressure on the pendant-crown, in the usual way. The stem of the watch-pendant passes out of the protector through a notch, a⁴, formed in the wall of the protector.

65 The section a' of the protector is provided with a self-closing cap or lid, a'⁵, by cutting through the said section along the line x, leaving only enough of the material uncut to form an elastic hinge, a⁶. (Seen best in Fig. 1.) This hinge a⁶ is arranged over the hinge of the cap b² of the watch-case, and it has sufficient elastic force to hold the cap a'⁵ closed normally, as 70 seen in Fig. 3; but when the cap b² is thrown up by its spring, as in Fig. 4, it raises cap a'⁵ also, the hinge-spring of the latter not being strong enough to resist the spring of watch-case cap.

75 The watch is inserted in the protector by first placing the body of the watch in the receptacle and then pressing the stem of the pendant down into the notch a⁴, the opening into which is narrower than the stem of the 80 watch-pendant. The material of the protector will yield sufficiently to allow the stem to pass, and will then close, so as to hold the stem by embracing it when it is once in place. The inner lining of chamois-skin serves to protect 85 the polished watch-case against abrasion, and the outer shell protects the watch against injury from blows unless the latter are very severe.

90 The material from which the outer shell of the protector is formed may be embossed or ornamented in any way to suit the taste, and may be colored, gilded, or bronzed, in order to make it tasteful and attractive. When the material of the protector is cut, as in forming 95

the cap a'^x , and the notch a^t , the raw edge thus produced may be finished in any manner, as by coating with varnish, for example.

In Fig. 5 I have shown my protector as adapted for use on an "open-face" watch. The construction is substantially the same as that already described, except that the watch B' is placed with its face down, as seen in the figure, so that the dial is visible through a circular opening, a'^x , formed in the section a^2 of the protector. By raising the cap a'^x the watch may be exposed for winding and setting, provided the watch is constructed for key winding and setting.

In Fig. 5 I have also shown a leaf-spring, e, to re-enforce or strengthen the spring-hinge a^x . Should such a spring be needed to compel the cap a'^x to remain closed normally, said spring may be inserted between the material forming the shell of the protector and the lining a^3 . This leaf-spring may be a thin strip of steel or other elastic metal or material.

It will be obvious that some moderately stiff tough non-metallic substance, like pressed

leather, will be best suited for making the 25 shell of my protector, and this is the material I prefer.

I prefer to use chamois skin as a lining for my protector, and I deem this the best material for the purpose; but other thin soft materials may be used with good results.

Having thus described my invention, I claim—

A watch-protector constructed of two cup-like sections of stiff leather joined together at 35 their margins, one of said sections having a slit, x , which extends part way around the section, whereby an integral self-closing cap, a'^x , is formed, and having also a notch, a^t , which extends from the said slit x down to the median line of the protector, as set forth.

In witness whereof I have hereunto signed my name in the presence of two subscribing witnesses.

JULIUS DEBRINKE.
